UNITED STATES PATENT OFFICE.

JOHN KRYNOCK, OF DUQUESNE, PENNSYLVANIA.

TIE AND RAIL-FASTENER.

1,029,376.

Specification of Letters Patent. Patented June 11, 1912.

Application filed March 6, 1912. Serial No. 681,888.

To all whom it may concern:

Be it known that I, JOHN KRYNOCK, a citizen of the United States of America, residing at Duquesne, in the county of Allegheny and State of Pennsylvania, have invented certain new and useful Improvements in Ties and Rail-Fasteners, of which the following is a specification, reference being had therein to the accompanying drawing.

10. This invention relates to ties and rail fasteners, and the objects of my invention are to provide a concrete or composite tie that can be used in lieu of wooden or metallic ties, and to furnish a tie of the above type 15 with novel rail chairs for firmly supporting rails or the confronting ends of rails.

Other objects of my invention are to provide simple and effective means for anchoring rail chairs upon the surface of a concrete 20 or composite tie, and to provide splice bars that can be easily and quickly placed in engagement with the rail chairs for supporting and maintaining the alignment of rails mounted upon the chair.

25. Further objects of my invention are to provide rail fasteners that can be easily and quickly installed for retaining the abutting or confronting ends of rails upon a tie, and to accomplish the above results by a mechanical construction that is highly efficient in connection with steam and electric railways.

With the above and other objects in view, the invention resides in the novel construction, combination and arrangement of parts 35 to be hereinafter specifically described and then claimed.

Reference will now be had to the drawing, wherein:

Figure 1 is a longitudinal sectional view 40 of a portion of a tie and rail fastener in accordance with this invention, Fig. 2 is a plan of the same, Fig. 3 is a plan of a detached chair, and Fig. 4 is a perspective view of a detached anchoring device.

45. A tie in accordance with this invention comprises an oblong concrete body 1 having the same dimensions as an ordinary wooden tie, said body having longitudinal metallic reinforcements 2 in the form of rods or bars 50 that extend from one end of the tie to the opposite end thereof.

The concrete body 1, adjacent to the ends thereof, is provided with a transverse recess 3 for a rail chair 4. The chair 4 is cut away 55 to provide a seat 5 for the base flanges 6 of

rails 7, having the ends thereof abutting upon said chair. The rail seat 5 is provided with vertical openings 8 having the upper ends thereof enlarged to provide recesses 9. Extending through the openings 8 into the recesses 9 are the upper screw threaded ends 60 of vertical parallel bolts 10 having the lower ends thereof connected by a plate 11 that is embedded within the concrete body 1. The plate 11 is arranged transversely of the concrete body and screwed upon the upper ends 65 of the bolts 10 are nuts 12 that retain the chair 4 upon the seat 3 provided therefor in the end of the concrete body 1.

The chair 4, at the sides of the seat 5, is 70 provided with slots 13 having the lower ends thereof enlarged by recessing the outer walls of the slots 13, as at 14 thereby providing overhanging lips 15.

Bracing the sides of the rails 7 are splice 75 bars 16 having the lateral flanges 17 thereof provided with angle edges 18 that extend under the lips 15, as at 19. After the splice bars 16 have been placed in position, they are connected to the rails 7 by transverse 80 bolts 20 and nuts 21.

The lips 15 of the rail chair prevent vertical displacement of the splice bars 16 and lateral displacement is prevented by the bolts 20 and the nuts 21.

What I claim is:

In a tie and rail fastener, the combination with rails, and a concrete tie provided with transverse recesses, of a chair mounted in each recess and provided with a seat for the confronting ends of said rails, a plate embedded in said tie, parallel bolts carried thereby and extending into said chair, nuts screwed upon said bolts beneath the ends of said rails for retaining said chair in engagement with said tie, said plate having slots formed therein with the outer walls of said slots recessed to provide overhanging lips, and splice bars connected to and bracing the sides of said rails, said splice bars 100 having the lateral flanges thereof provided with angle edges extending into the slots of said chair and engaging under said lips.

In testimony whereof I affix my signature in the presence of two witnesses.

JOHN KRYNOCK.
